SCREEN APPARATUS FOR PIVOTED SASHES

Filed April 3, 1925

Patented Feb. 12, 1929.

1,701,701

UNITED STATES PATENT OFFICE.

JOHN E. SODERGREN, OF MINNEAPOLIS, MINNESOTA.

SCREEN APPARATUS FOR PIVOTED SASHES.

Application filed April 3, 1925. Serial No. 20,383.

This invention relates to screens and screen apparatus for pivoted or swinging sashes.

The main object of the invention is to provide simple but highly efficient screen apparatus for pivoted sashes to be used in combination with upper and lower screens disposed respectively on the opposite sides of the sash screen to close all openings from outside of the sash with the interior of a building when the sash is swung to any open position.

The upper and lower screens employed in any swinging sash must, of course, be spaced sufficiently above and below the axis of the sash to permit clearance thereof when the sash is swung, leaving, of course, openings between the front and back of the sash and the screens when the sash is open. This invention provides simple but efficient means for closing these openings and thereby excluding flies and other insects.

A further object of the invention is to provide apparatus, including a means mounted adjacent the lower edge of the upper sash for closing the space between the upper screen and the outside of the sash, and means rigidly carried by the sash for closing the opening between the lower screen and the inner side of the sash.

It is a still further object to provide in such apparatus, means for closing off the openings which are formed at the ends of said closing means when the sash is swung to certain positions.

These and other objects of the invention will be apparent from the following description made in connection with the accompanying drawings, wherein like notations refer to similar parts throughout the several views, and in which

Fig. 1 is an elevation of the outer side of a swinging sash mounted in the sash frame and equipped with apparatus in accordance with this invention;

Fig. 2 is a vertical section taken on the line 2—2 of Fig. 1 with the moved position of the sash indicated by the dotted lines;

Fig. 3 is a horizontal fragmentary section taken on the line 3—3 of Fig. 1;

Fig. 4 is a similar section taken on the line 4—4 of Fig. 1; and

Fig. 5 is a fragmentary vertical section of a swinging sash equipped with the preferred form of the invention swung out to open position.

Referring to the drawings, a standard frame for swinging sashes is illustrated, hav-

ing the angle bar side members 6 and the similarly constructed transverse top and bottom members 7 secured therebetween. Weathering members in the form of channel bars 8 are secured on the inner sides of the side members 6 extending from points below the axis of the sash to the bottom of the frame, affording the two weathering points as best seen in Fig. 4, one at either side of the sash. A pair of rugged oppositely aligned angular brackets 9 are rigidly secured to the inner sides of the side members 6 of the frame having aligned bearings at their outer ends disposed in the interior side of the frame. Transverse weather strips 7^a and 7^b are secured at the top exterior and bottom interior of the frame, respectively, to which the screen mounting strips 10 are secured.

A standard swinging sash, designated as an entirety by the letter A, comprises the side muntin boards 12, the angular bottom and top limit stops, one extending on the interior and the other on the exterior of the frame, respectively, and the usual glass pane 12^a. Brackets 11 are secured at either side of the sash in alignment with brackets 9 carried by the frame and are provided with oppositely aligned bearings through which and through the bearings and brackets 9, nutted bolts 11^a are secured, pivotally mounting the sash A in the sash frame.

Channeled weathering members 13 are secured at either side of the sash A extending from points slightly above the axis of said sash to the top of the frame, having the two weathering points adapted to contact the sash frame along the exterior and interior sides thereof.

A bracket 14^a, having depending arms at either end, is secured across the outer side of the sash frame on a line somewhat above the axis of the sash, to which is secured the strip 14 extending between the side muntin boards 12 of the sash and having the upstanding shoulder 14^b on its inner side disposed in close relation to the pane 12^a of the sash when the sash is closed. The top screen 15 is mounted between the upper weather strip of the sash frame 7^a and the upper portion of the strip 14 and the bottom edge of said screen extends directly over the angular shoulder 14^b. Arcuate blocks 16, having a radius substantially equal to the distance between the axis of the sash and the lower edge of the strip 14, are oppo-

sitely alined and secured to the side muntin boards 12 of the sash on the exterior of the sash and cover the space between the side muntin boards and the lower edge of the 5 plate 14 regardless of what position the sash A is swung to, since the arc of the outer edge of said blocks is centered on the axis of said sash.

A transversely extending rectangular flap 10 17, having downturned flanges at its outer edge and end portions, extends between the side muntin boards 12 of the sash on the interior of the same and is provided with the longitudinal channel portion 17^a at its inner edge, engaging the shoulder 14^b and forming a hinge therewith, the axis of which hinge lies directly beneath and parallel with the bottom edge of the screen 15, as shown in Figs. 2 and 5. When the sash is in closed 20 position, as illustrated in Fig. 2, the flap 17 will be held between the screen 15 and the pane 12^c, with its axis, nevertheless, directly beneath the bottom edge of said screen and, obviously, when the sash is swung, the flap 25 will fall therewith, the outer flanged edge engaging the pane 12^c whereby the space between the arcuate blocks 16 and the lower edge of top screen 15 and the pane 12^c will be at all times covered by said flap regardless 30 less of the position of sash A.

The lower screen 18 is mounted on the interior side of the sash frame extending from a line slightly below the axis of the sash to the bottom of said frame, the bottom of said 35 screen being held in the strip 10. A transverse plate 19, having a semi-cylindrical main portion, is rigidly secured across the interior side of the sash with its inner end in close relation to the pane of said sash and having 40 its semi-cylindrical portion centered about the axis of said sash on a radius approximately equal to the distance between the axis of sash A and the top of the lower screen 18. Obviously, since the semi-cylindrical portion of plate 19 is so centered, the space 45 between the interior side of the pane 12^c and the top of the lower screen 18 will at all times be covered when said sash is swung, and since the pivots of the sash are on the 50 interior side of the sash frame, plate 19 will be swung between the sides of the sash frame having its ends covered thereby.

In certain positions of the sash, however, 55 the ends of the flap 17 will not be covered by the arcuate blocks 16 and small apertures would be formed were it not for the vertically swinging depending plates 20 pivoted to the outer sides of the arcuate block 16 adapted to have their lower edges engage 60 the top edges of the limit stops or weathering members 8. By means of these swinging plates 20 all passages at the ends of the flap 17 are closed regardless of the position of the sash.

From the above, the operation of the device

is probably obvious, but may be briefly summarized as follows:

When the sash is closed, the flap 17, as has been stated, is disposed between the screen 15 and the exterior of the pane 12^c, while the 70 transverse semi-cylindrical plate 19 extends slightly into the interior of the room in which the sash is mounted. Upon swinging the sash, the hinged flap 17, having its axis disposed beneath screen 15 and outwardly of its longitudinal free edges, will drop, engaging the pane 12^c. Simultaneously the transverse plate 19 will be swung with the lower edge of its cylindrical portion engaging the top edge of the lower screen 18. The ends of the flap 17 will be covered by the arcuate blocks 16 and the depending swing-plates 20. It will, therefore, be seen that the sash may be swung open to any position without leaving apertures for flies or insects to gain entrance into the interior of the room.

From the foregoing description, it will be apparent that simple but highly efficient apparatus has been invented for use in connection with pivoted sashes and screens therefor.

Extensive actual usage has proven the invention to be highly successful for the purposes intended.

It will, of course, be understood that various changes may be made in the form, details, proportions and arrangement of parts without departing from the scope of the invention, which, generally stated, consists in the apparatus as shown and described and defined in the appended claims.

What is claimed is:

1. In swinging sash provided with a screen, apparatus for closing the space between said screen and said sash comprising a transverse flap hinged adjacent the lower edge of the screen and held against the pane of said sash, and a pair of narrow, spaced closure members fixed to said sash at the ends of said flap extending in a plane normal to the pane of said sash and having an outer edge concentric with the pivot of said sash for closing the space between the ends of said plate and said sash.

2. In swinging sash provided with a screen, apparatus for closing the space between said sash and said screen having in combination a rigid flap swingably mounted from the lower edge of said screen with its free end held against the pane of said sash by gravity, narrow closure members carried adjacent each longitudinal edge of said sash at right angles to the pane of said sash and having arcuate outer edges concentric with the pivot of said sash, said edges being disposed tangential to the lower edge of said screen and plates loosely pivoted to said closure members extending between the longitudinal edges of said sash and its sash frame.

3. In swinging sash provided with a screen,

apparatus for closing the space between said screen and said sash, comprising an elongated plate at the lower edge of said screen having a narrow perpendicular flange, a flap 5 having an angle portion engaging said flange to permit swinging movement of said flap relatively thereto, said flap being of greater width than the distance between the pane of said sash and said plate in any position of

said sash, whereby gravity will hold said flap against the pane of said sash when said sash is opened and members at the ends of said plate extending normal to the pane of said sash for closing the space between the ends of said flap and said sash. 10 15

In testimony whereof I affix my signature.

JOHN E. SODERGREN.
